UNITED STATES PATENT OFFICE.

FERDINAND E. CANDA, OF NEW YORK, N. Y.

BALL-ROLLING MACHINE.

1,225,765.

Specification of Letters Patent.

Patented May 15, 1917.

Application filed January 11, 1916. Serial No. 71,504.

To all whom it may concern:

Be it known that I, FERDINAND E. CANDA, a citizen of the United States of America, and a resident of New York, in the county 5 of New York and State of New York, have invented certain new and useful Improvements in Ball-Rolling Machines, of which the following is a specification.

My invention relates to apparatus for 10 forming balls and other bodies of rotation, and comprises improvements upon the machine for the same purpose illustrated and described in my application for Letters Patent filed June 10, 1915, Serial No. 33,223.

15 The object of my invention is to provide improved means for forming balls and other objects of rotation with great rapidity and at low cost and with apparatus of a simple character.

20 I will now proceed to describe my invention with reference to the accompanying drawings, and will then point out the novel features in claims. In said drawings:

Figure 1 shows a side elevation of a ball 25 rolling machine embodying my invention, and

Fig. 2 shows a vertical transverse section of the machine.

Fig. 3 shows a fragmentary transverse 30 axial section of the machine.

Fig. 4 shows a fragmentary side elevation of one of the outer frame members, looking toward the near side of that frame member, the view showing particularly the means 35 for holding the breast-die and drum in proper relative positions.

Fig. 5 shows a transverse section on the line 5—5 of Fig. 4.

Fig. 6 shows a transverse section on the 40 line 6—6 of Fig. 2, and shows particularly the stripper plate by which the finished balls are removed positively from the roll or drum.

Fig. 7 is a fragmentary axial section 45 through the registering grooves of the roll and breast, showing the sectional profile of those grooves.

In the drawings, 1 designates a roll shell, 50 which is shown in this instance as hollow, with reversely tapering interior surfaces 2, said roll shell mounted upon tapered disks 3 and 3', one of which has a hub 3' keyed to the shaft 4, the other disk 3 having a taper fit on that hub, the two disks being 55 held together by bolts 5. The shaft 4 is mounted in bearings in suitable pedestals

6 themselves mounted upon a base 6'. Any suitable means is provided for driving the shaft 4; for example, a gear wheel 7 mounted upon shaft 4 and an intermeshing gear wheel 8 mounted upon a shaft 9.

The roll 1 is provided with a number of grooves 10 of a profile corresponding to that of the object to be produced. If this object is to be spherical the grooves 10 of the roll 15 are of approximately semi-circular profile. Adjacent the roll 1 is a breast, or reducing die, 11, provided with corresponding and registering grooves 12. The curvature of this breast or reducing die is a spiral, or an 20 approximation to a spiral; or it may be circular but of larger radius than the roll 1 and eccentric to the roll 1; the construction being such that the space between the breast and roll is relatively wide at one side and 25 grows progressively narrower toward the other side of the reducing die.

I have found that the stresses set up in 30 the operation of this machine are at times very great; particularly when, through im- 35 proper heating, the blanks from which the balls are to be formed are harder than they should be. For this reason I have found it

desirable to support the breast or reducing die, 11, by a frame member 14 of approxi- 40 mately semi-circular form extending over the top of the roll 1 from one side of the machine to the other, and secured at both ends to the pedestals 6 by very massive bolts 45 14'. This member 14 is, for convenience in 50 construction and assembling, formed in three parts, viz.—two side members 14^a, and an intermediate half-ring 14^c, interlocked relatively by ribs 14^b formed on the half-ring 14^c and engaging corresponding grooves 55 in members 14^a, members 14^a and 14^c being held together by through-bolts 14^d. To permit visual observation of the action of the 60 machine, the side members 14^a are of spoked 65 construction; i. e., they each consist of an outer rim 14^e and a hub portion 14^f connected by spokes 14^g; the spaces between 70 these spokes permitting visual inspection of the progress of the material acted upon 75 through the machine.

The reducing die, 11, is supported from 80 the frame member 14 by means of screw 85 bolts 14^h; and thrust screws 14ⁱ are also distributed liberally over the back of the reducing die, so that the thrust on this die 90 in the operation of the machine may be 95 transmitted to the massive supporting ring 100 105

14^e. It will be apparent that by means of the supporting screws 14ⁱ and the thrust screws 14^k a considerable adjustment of the reducing die 11 with respect to the drum or roll 1 may be obtained; *i. e.*, the angle of the reducing die with reference to the roll may be varied considerably, also the distance between the reducing die and the roll may be varied considerably.

10 It is important that the reducing die or breast 11 shall be held with its grooves in precise registry with the grooves of the roll. Therefore certain of the spokes 14^h of the frame members 14^f are spanned by yokes 14^m and 14ⁿ connected by bolts 14°, which bolts carry, at their inner ends, rubbing shoes 14^p adjusted to bear lightly yet firmly against the sides of the roll 1. Also, these spokes 14^h carry set screws 14^q whereby the lateral position of the reducing die 11 may be adjusted.

15 It may occasionally happen that the ends of the rods from which the balls are formed project slightly beyond the side faces of the roll. As will be seen particularly from Fig. 3, the rubbing shoes 14^p and the bolts supporting them are spaced apart from the set screws 14^q a sufficient distance, radially, to permit such projection of the end portions of the rods from which the balls are formed.

16 designates a so-called finishing die located at the exit end of the reducing die or breast 11, and supported by bolts 17 and spaced from the frame member 14 by adjustable set screws 18, so that the angle and distance of this finishing die with respect to the roll 1 may be adjusted independent of the adjustment of the reducing die 11. I have found this separate finishing die a very important feature of the machine. The main reducing die 11 is necessarily set, with respect to the roll 1, so as to cause very considerable reduction of the stock in passing between that roll and die; and it is practically necessary that the inner or working surface of this die 11 shall be a true curve, either a true segment of a circle or a true segment of a spiral which may be generated readily. Therefore, it is not practicable to change the curvature of this main reducing die 11, near its exit end, to provide for less reduction during the last portion of the travel of the material through the machine; yet unless provision be made for very little reduction only during the last portion of the travel of the material through the machine, that material, as it emerges, will have a pronounced rib, in a plane parallel to the axis of rotation. The separately adjustable finishing die 16 obviates this objection; and that die may be set to give only such very slight reduction as is necessary to insure feeding of the material past that finishing die; the formation of a rib such as referred

to on the material passing through the machine is thereby obviated and balls of very perfect contour are produced.

70 The ribs between the grooves of this finishing die may also be of such height and of such sharpness as will cause them to cut, or at least to reduce to very small dimensions, the neck formed between adjacent balls by the rolling operation, so that the balls formed will be separated from one another as they leave the machine. This finishing die, being a relatively small object, is readily removed and its grooves corrected in form, and the ribs sharpened if necessary, from time to time. The finishing die should have a length, with reference to the direction of progress of the material through the machine, somewhat greater than the circumferential length of the finished ball.

75 It is very important in a machine of this sort that the blanks from which the balls are to be formed shall be introduced between the reducing die 11 and the roll 1 in a direction exactly parallel to the axis of rotation. Furthermore, since the blanks 80 at first move upward, it is necessary that means be provided for lifting them and forcing them into the space between the roll and reducing die. Therefore I have provided a blank-feeding device consisting 85 of a shelf 18 pivoted at 19 to the frame 90 of the machine and arranged to be elevated when desired by means of a rod 20 connecting said shelf 18 to a pivoted pedal 21. In introducing blanks into the machine a 100 blank is placed upon this shelf 18 and permitted to roll down until it touches the surface of the roll 1; and then, by actuation of the pedal, the blank is raised and forced into the space between the roll 1 and die 105 11. In Fig. 2 this shelf 18 is shown in elevated position.

Sometimes the balls tend to cling slightly to the surface of the roll 1; therefore a toothed stripper 22 is provided as shown 110 particularly in Figs. 2 and 6; the teeth of this stripper being located within the grooves of the roll 1, and serving to strip the balls, if necessary, from that roll, whereupon the balls roll down a shelf 24.

115 An important feature of my invention is the sectional profile of the grooves of the roll and breast. In the production of balls by means of grooved dies it has been found that if the die grooves are semi-circular or approximately so, in cross section, the resultant balls will be flattened very considerably at the poles. I have found that by broadening the grooves progressively outward, this difficulty is overcome, 120 and that by proper proportions substantially truly spherical balls may be produced; a somewhat surprising fact, since such balls have considerable lateral clearance in the grooves of the dies in the polar 125 130

regions of such balls; nevertheless it is a fact as stated that, with the die grooves broadened as described, substantially truly spherical balls are produced; and this has been found in actual practice in making balls on a large commercial scale. In Fig. 7 I have indicated a profile of die grooves which I have found desirable; the dotted circle 25 showing the cross section of the true sphere which the balls produced in such grooves approximate very closely. It will be observed that the grooves 10 are approximately of circular cross-section near their apices, while near the bases of the grooves (*i. e.*, the tops of the ribs) the walls of said grooves are approximately straight and approximately tangent to the circle 25, but at quite a noticeable angle to the axis of rotation.

26 in Fig. 2 designates a tempering tank into which the balls drop from the shelf 24. It is desirable to carry away from the machine the end portions of the rods which are cut off by the action of the outside ribs of the dies. To this end I provide troughs 27 shown in dotted lines, in Figs. 1 and 2, and shown in cross section in Fig. 3, and in plan in Fig. 6. These troughs are angle-irons located in the spaces between the sides 30 of the drum and the supports 14^b, and supported partly by the support 28 for the stripper 22 and in part by yokes 29 embracing the metal spokes of the supports 14^b. At the lower ends of these troughs 27, their flanges 30 are bent outwardly as shown particularly in Fig. 6, so as to guide the cropped ends of the rods away from the machine.

It is convenient to carry these troughs 27 well back, and preferably back of the center of the machine, because, in some cases, the reducing die 11 is shaped and adjusted so that the cutting of the bars to or near the center is done in the early part of the rolling operation; and of course in such case the ends of the bars may be cut off early in the progress of those bars through the machine.

What I claim is:—

1. A machine for forming balls and other objects of rotation, comprising a base, a grooved roll mounted for rotation with respect to said base, said base having pedestals on opposite sides of said roll, a frame member spanning the roll and secured to said pedestals, and a grooved breast located in proximity to the roll and with its grooves in registry with the grooves of the roll, said breast supported by said frame member.
2. A machine for forming balls and other objects of rotation, comprising a grooved roll and a correspondingly grooved breast, and a support for said breast comprising two side members on opposite sides of said

roll, and an intermediate member spanning the roll and firmly secured to said side members and also connected to the breast to support the same.

3. A machine for forming balls and other objects of rotation, comprising a grooved roll and a correspondingly grooved breast located in proximity to the roll, a base, a support for said breast rigidly secured to said base, and means, carried by said support and engaging the sides of said roll, and arranged to prevent lateral motion of said roll.

4. A machine for forming balls and other objects of rotation, comprising a grooved roll and a correspondingly grooved breast located in proximity to the roll, a base, a support for said breast rigidly secured to said base and spanning the roll and having spokes near the sides of said roll, and means engaging said spokes and comprising shoes bearing against the sides of the roll and preventing lateral motion thereof.

5. A machine for forming balls and other objects of rotation, comprising two grooved die members, one of which is movable with respect to the other, the grooves of such die members registering respectively, and the space between said die members growing progressively narrower in the direction of motion of one of said members with relation to the other, and means for introducing material to be acted upon between said die members comprising a movable support for such material to be acted upon, and means for moving such support toward the entrance to the space between said die members.

6. A ball forming die comprising a grooved die member adapted for coaction with a correspondingly grooved die member and for the rolling through its groove of an object to be formed into a ball by the action of such groove, the said groove being of approximately circular curvature at and near its apex and thence broadening outward to beyond true circular curvature toward the base of the groove.

7. A machine for forming balls and other objects of rotation, comprising two grooved die members, one of which is movable with respect to the other, the grooves of such die members registering respectively, and the space between said die members growing progressively narrower in the direction of motion of one of said members with relation to the other, said die members being adapted to receive between them a bar and by their action to form that bar into a plurality of balls and to cut off the extreme ends of the bars, and means adapted to receive the ends so cut off and to carry them away.

8. A machine for forming balls and other objects of rotation, comprising a grooved roll and a correspondingly grooved breast

located in proximity to the roll, the grooves of said roll and breast registering, and the space between said roll and breast growing progressively narrower in the direction of 5 rotation of the roll, said roll and breast being adapted to receive between them a bar and by their action to form that bar into a plurality of balls and to cut off the extreme ends of the bars and means adapted

to receive the ends so cut off and to carry 10 them away.

In testimony whereof I have signed this specification in the presence of two subscribing witnesses.

FERDINAND E. CANDA.
